UNITED STATES PATENT OFFICE.

JOHN HARVEY FARREL, OF CAMDEN, NEW JERSEY, ASSIGNOR TO HENRY W. MAYBAUM, OF PHILADELPHIA, PENNSYLVANIA.

POCKET-LAMP.

SPECIFICATION forming part of Letters Patent No. 451,301, dated April 28, 1891.

Application filed December 13, 1890. Serial No. 374,536. (No model.)

To all whom it may concern:

Be it known that I, JOHN HARVEY FARREL, a citizen of the United States, residing at Camden, in the county of Camden and State of New Jersey, have invented certain new and useful Improvements in Pocket-Lamps, of which the following is a specification.

My invention relates to that class of lighting devices designated as "pocket-lamps" provided with means for feeding and exploding by contact with a device a fulminating pellet, cap, or ignitable material.

My invention consists of a lamp of the construction and having the parts and devices arranged for operation substantially in the manner hereinafter described, and particularly as pointed out in the claims.

The nature of the invention and the characteristic features thereof will be more fully understood from the accompanying drawing, forming part hereof, which represents in perspective a pocket-lamp embodying the features of my invention, with the divided housing, oil-receptacle, and parts thereof exposed to view.

Referring now to the drawing, the exterior housing of the lamp is divided and is composed of two members A and A', connected together by means of a hinge a.

A² is an exterior lid or cover attached to one of these members by a hinge a', and adapted to close the upper portion of the housing and extinguish the lamp. In the drawing the lid A² is represented as hinged to the member A; but, if preferred, it may be hinged to the member A'. The lid A² is retained in a closed position by means of a spring-catch a² of any preferred construction.

A³ is a receptacle adapted to receive oil or an absorbent material or substance saturated with oil. This receptacle A³ is connected with or attached to one of the members A or A'. In the drawing it is represented as attached to the member A; but, if preferred, it may be attached to or connected with the member A'.

A⁴ is an interior cover or lid mounted in or on or attached to the oil-receptacle A³ in any suitable manner—for example by means of a hinge a⁴—and adapted to be opened in order to fill the same. This cover A⁴ is provided

with an aperture a⁵, adapted to permit of the passage of one extremity x' of the wick x from the interior of the receptacle A³ through the lid or cover A⁴, so that when the latter is closed the extremity x' of the wick x occupies a position adjacent to the point at which the fulminating pellets, drops, or bits of ignitable material are exploded.

a⁶ is a lug or latch-pin attached to the member A² and adapted to penetrate an aperture a⁷, formed between the wall of the receptacle A³ and the member of the housing A, and engaging in a slot a⁸, formed in the interior lid or cover A⁴ of said receptacle, and adapted to retain the latter in a closed position when the member A' of the housing is closed.

b is a retaining pin or lug, preferably secured to the wall a⁹ of the oil-receptacle A³.

c is a stud pin or support provided with a loose sleeve c', located in proximity to the exposed end x' of the wick x when the interior lid or cover A⁴ is in its normal or closed position.

d is a toothed disk mounted on a pin d' and arranged so that a portion of its periphery projects through a slot formed in the wall of the housing and extending outside thereof. The pin d' of the disk d is bifurcated for a purpose to be presently described.

e is a spring having one extremity thereof in engagement with the lid A² in order to maintain the latter normally in an open position, and having the other extremity thereof in contact with the toothed disk d in order to prevent said disk from being turned in a reverse direction. This spring e is preferably composed of a continuous strip of metal and is secured in place by being fitted into a recess e', formed in a fixed lug e², and caused to engage with one of the internal corners of the housing, as at e³.

e' is a bend or curve formed in the spring-metal strip e at the point where it engages in the recess e' of the lug e² in order to prevent vertical displacement thereof. It may be remarked that this arrangement of the spring e not only affords a simple, efficient, and convenient means for the purposes mentioned, but also presents a device having important resilient effects in action.

f is a scratcher or ignitor of any suitable

construction—such, for example, as a coil of wire—having one extremity f' in contact with the support c or sleeve c' and the other extremity f^2 attached to the lid or covering A^4 of the oil-receptacle in any suitable manner. For instance, as shown, the extremity f^2 of the spring f is bent so as to form a shank f^3 and is attached to the cover A^4 by means of loops f^5 and f^6 , struck up or otherwise formed therein. These loops f^5 and f^6 are disposed at an angle to each other, so that the scratcher or ignitor f is firmly secured to place without the employment of solder. It may be remarked that the pressure exerted by the extremity f' of the scratcher or ignitor f may be increased or diminished by opening the lid or cover A^4 and bending the extremity f' downward by means of the fingers or in any other convenient manner. Moreover, inasmuch as the cover A^4 is normally retained in a closed position by the pin a^6 , the extremity f' of the scratcher or ignitor f is normally held in contact with and presses against the sleeve c' or support c .

25 g is a narrow strip or ribbon of muslin, linen, or other suitable material, provided with percussion-caps or fulminating pellets g^2 , disposed at suitable distances apart along the same. The narrow ribbon or strip g , formed into a coil, is inserted onto the retaining pin or lug b , and then led around the loose sleeve c' of the stud-pin or support c , beneath the extremity f' of the scratcher or ignitor f , and into proximity to the exposed extremity x' of the wick x , and the forward end thereof is passed between the bifurcated pin d' , and then coiled around the same, as shown in the drawing. The cover A^4 of the oil-receptacle is then closed, so as to bring the extremity x' of the wick x and scratcher or ignitor f into an operative position with relation to the pellets or caps g^2 , and the cover A^4 is secured in a closed position by turning the members A and A' toward each other, so that the pin or stud a^6 engages in the slot or groove a^8 . The disk d is then actuated by the thumb or in any other preferred manner and the narrow strip or ribbon g fed upward from the retaining-pin b around the loose sleeve c' of the stud pin or support c , whereby the individual caps or pellets g^2 are brought into frictional contact with the scratcher or ignitor f and exploded, and the explosion of the pellets or caps causes the extremity x' of the wick x to be lighted.

55 The tape, strip, or ribbon g , after its caps or pellets g^2 have been exploded simultaneously with the feeding of the same, is wound around

the bifurcated pin d' of the toothed disk d until the entire strip has been rendered useless by the consumption of all the caps or 60 pellets thereof, when the strip or ribbon may be readily removed and another inserted by simply causing the lamp to assume the position illustrated in the drawing.

The stud pin or support c , instead of being 65 provided with a loose sleeve c' , may be formed in one piece.

Although the present invention has been described with relation to certain mechanism for feeding and exploding the caps or fulminating pellets, still it is not limited to the employment of such mechanism, because it is applicable in whole or in part to any type of pocket-lamp provided with means for exploding a fulminating substance in proximity to 75 a wick.

Having thus described the nature and objects of my invention, what I claim herein as new, and desire to secure by Letters Patent, is—

1. A pocket-lamp having a divided housing provided with a cover and comprising two members, whereof one is provided with a reservoir having a hinged cover through which a wick passes, a scratcher or ignitor attached 85 to said cover, a support disposed adjacent thereto, a fulminate-carrier adapted to be pulled or drawn over the support to ignite the fulminates thereof, and the other of said members provided with a pin adapted to engage 90 said hinged cover and hold said divided housing together, substantially as set forth.

2. A pocket-lamp having a two-part housing provided with a cover, an oil-absorbent material receptacle mounted therein and provided with a cover having loops struck up therefrom and a wick extending through said cover, a scratcher or ignitor held in and by said loops, a supported fulminate strip or carrier, and means for pulling or drawing 100 said strip or carrier into contact with said scratcher or ignitor, for the purposes set forth.

3. A pocket-lamp provided with a housing having a hinged cover, a disk, and a spring engaging with a lug in said housing and the 105 extremities thereof in contact with said cover and disk, for the purposes set forth.

In witness whereof I have hereunto set my signature in the presence of two subscribing witnesses.

JOHN HARVEY FARREL.
